(57) **CLAIM**

The ornamental design for a handle for a utensil, as shown and described.

DESCRIPTION

FIG. 1 is a front elevational view of a handle for a utensil according to the present design;

FIG. 2 is a side elevational view thereof; the other side elevational view being the same;

FIG. 3 is a back elevational view thereof; and,

FIG. 4 is a top view thereof, drawn on an enlarged scale. The broken lines shown in FIGS. 1 and 4 are illustrative of environmental structure only and form no part of the claimed design.
